CARBON SUPPLY AND CONTROL FOR WRITING MACHINES

Carl R. Mabon, Niagara Falls, N. Y., assignor to
Gilman Fanfold Corporation, Niagara Falls,
N. Y., a corporation of Delaware

Application November 6, 1940, Serial No. 364,507

15 Claims. (Cl. 197—126)

This invention relates to improvements in writing machines, and more particularly to an improved carbon or transfer strip supporting and controlling device adapted for interleaving transfer strips from a supply in transfer relation with the record strips, so as to transfer inscriptions made on the top or original record strips. While the improved carbon supply and control device is adapted for different forms of writing machines, it is herein disclosed for illustrative purposes as applied to a writing machine of the flat platen type wherein the writing machine proper moves over the flat platen for letter spacing. Also, for illustrative purposes the improved supply device is disclosed for use in connection with assemblies of long continuous record strips of the fan-folded type, but it is adapted also for use in connection with record strip assemblies having separate record strips assembled in superposed manifolding relation.

It is a general object of the invention to provide an improved transfer strip supply and control for machines of the class mentioned whereby the carbon or transfer strips are led from a supply, such as carbon strip spools and guided transversely into interleaved relation with the record strips and then turned into the longitudinal path of the record strips so as to assume interleaved transfer relation at the parts of the platen where the inscriptions are being entered. Improved means are provided for introducing the transfer strips in the inscription receiving positions.

A further object of the invention is to provide an improved arrangement of strip turning devices whereby the carbon or transfer strips are turned into longitudinal alignment in transfer relation with the record strips, while at the same time avoiding any obstruction or binding of the free feeding movement of both the record and transfer strips into writing position upon the platen.

A further object is to provide a carbon supply and control device for machines of the class mentioned having an improved manner of mounting and positioning the carbon strip turning devices, whereby the carbon strips can be quickly and easily threaded into correct interleaved relation with the record strips.

A further object is to provide for machines of the class mentioned an improved carbon supply and control device whereby the depleted or used end portions of the carbon strips can be quickly and easily removed and fresh lengths introduced

into inscription transfer relation upon the writing platen.

According to another feature of improvement the carbon supply and control device is so constructed and arranged that it can be quickly and easily installed in operative position on machines already in use, very little or no alterations in the machine being required in order that the carbon supply and control device may be installed. The device is so constructed and arranged that it can be lowered from above into operative position between the rearwardly extending frame members of the writing machine, or, if desired, it may be raised from below the side frame members into operative position. The supply device is constructed and arranged so that the parts thereof lie wholly within the vertical planes of the side frame members of the writing machine, thus avoiding obstruction with outside objects and enabling installation in operative position on two writing machines of the class mentioned, placed side by side, sometimes known as "double barreled" machines.

According to another feature of improvement the carbon supply and control device embodies a longitudinal reciprocable carriage supporting the carbon supply rolls and having an improved operating connection therefor readily accessible to the operator and having a convenient latching or locking device with control therefor for holding the carriage in either of its forward or rearward positions.

Another feature of improvement resides in the automatic control means for normally holding the carbon supply spools against rotation for paying out the carbon strips when the reciprocating carriage is in its rearward or normally operative position, and for automatically releasing the spools to rotation when the carriage is moved into its forward position.

A further object of the invention is to provide an improved turning device or frame for the carbon strips having a simple and practical means for mounting it in operative position, whereby it can be swung or turned on pivotal mountings for threading the carbon strips into operative position and moreover being light and strong and of relatively low manufacturing cost.

Other objects of the invention will be in part pointed out in the following detailed description of certain illustrative but preferred embodiments of the invention, and will be in part obvious as the disclosure proceeds.

The invention accordingly comprises the features of construction, combination of elements,

and arrangement of parts, which will be exemplified in the construction hereinafter set forth and the scope of the application of which will be indicated in the claims.

For a more comprehensive disclosure of the nature, objects and advantages of the invention reference is had to the following detailed description of the illustrative embodiments and to the accompanying drawings, in which:

Fig. 1 is a fragmentary side elevation of a writing machine of well known construction and having the improved carbon strip supply and control applied thereto.

Fig. 2 is an enlarged fragmentary plan of the rearward part of the machine of Fig. 1, showing the improvements.

Fig. 3 is a vertical longitudinal elevation and section taken substantially on the line 3—3 of Fig. 2, looking in the direction of the arrows.

Fig. 4 is an enlarged elevation and section taken substantially on the line 4—4 of Fig. 2, looking in the direction of the arrows.

Fig. 5 is an enlarged vertical transverse section showing the releasable supporting means for holding the carbon supply device in operative position.

Fig. 6 is a detailed section on the line 6—6 of Fig. 3.

Fig. 7 is an enlarged partially diagrammatic transverse section showing the interleaved record and carbon strips as they appear when assembled for inscription upon the writing platen.

Fig. 8 is a detailed perspective view of one of the carbon strip turning frames.

Fig. 9 is an enlarged central longitudinal section through one of the carbon supply spools.

Fig. 10 is a detailed vertical longitudinal section through the latching and operating device for reciprocating the carbon carriage.

Fig. 11 is a detailed section substantially on the line 11—11 of Fig. 10.

Fig. 12 is a detailed perspective view showing the latching device of Fig. 10.

Fig. 13 is a fragmentary enlarged elevation and section showing the automatic holding and releasing device for the carbon supply spools.

Fig. 14 is a detailed perspective view of a part of the spool holding mechanism shown in Fig. 13; and

Fig. 15 is a view similar to Fig. 13 but showing a modified embodiment of the automatic holding means for the carbon supply spools.

Referring to the drawings for a detailed description of the illustrative embodiments of the invention there shown, and first to the embodiments of Figures 1 to 14, inclusive, the improved carbon supply and control device is shown as installed on a typewriting machine of the flat platen type well known in the art. This writing machine is supported upon a pedestal 17 that can rest upon the floor in an upright position, and carries at its upper extremity a supporting frame indicated generally at 18, having side frame members 19 carrying at the forward parts thereof a flat plate or platen 20 upon which the record and transfer strips are supported when receiving the writing inscriptions. As shown, these side frame members extend rearwardly from the platen for some distance and the record strip assembly 21 is led over rearward guides from a supply 22 of zigzag folded strips in writing position upon the platen. The typewriting machine 23 is mounted upon rack bars or rails 24 attached to the frame members 19 for movement therealong to effect line spacing.

At the forward end of the frame 18 there is a movably mounted transverse clamping and tearing bar 25 mounted upon swinging and supporting arms 26 and beneath which the forward end 5 of the strip assembly passes for holding the same in position. This bar also serves as a severing edge or blade for effecting severance of the forwardly moved end portions of the strip assembly that is ordinarily provided with transverse weakened severance lines 21'. This clamping and tearing bar is connected for control by a pedal operating member under the control of the operator, who sits at the forward end of the machine. Since this operating mechanism is well known in the art and is disclosed, for example, in the Simonson Patent No. 2,110,611 issued March 11, 1938, it need not be described in detail here.

As shown in Figures 1, 2 and 3 the improved carbon supply and control device indicated generally at 26 is mounted upon and carried by the rearwardly extending portions of the side frame members 19, being interposed between the latter and depending therefrom. As best seen in Figures 2, 3 and 4, this supply device embodies a framework having transverse end frame members 27 and 28 and longitudinally disposed side frame members or rods 29. The end and side frame members are connected together to form a light but strong supporting frame that can be quickly and easily attached in operative position between the frame members 19 and also provides a support for the longitudinally reciprocating carbon strip supply carriage indicated generally at 30.

For supporting the framework for mounting the supply carriage 30 in operative position, the rear end frame member 27 is formed with hook-like supporting arms 31 extending upwardly and outwardly therefrom and having the hook-like formation thereof adapted for supporting engagement with the transverse supporting bar or rod 32 that is connected at its opposite ends to the side frame members 19 of the writing machine. These hook-like supporting members 31 can be easily hooked over the transverse supporting bar without making any alterations in the writing machine frame, since this bar is a standard part of the machine frame. The supporting arms 31 may, as shown, carry a strip guiding plate 33 and a transverse connecting bar 34 extends between the two opposite arms 31.

At the forward end of the frame of the carbon supply device, the end frame member 28 is provided with retractable parts to form releasable supporting attachments cooperating with the side frame members 19. For this purpose the supporting member 28 is in the form of a hollow tube mounted in attaching blocks or castings 35 to which the longitudinal or side frame members 29 are attached. Slidably mounted within this tube 28, as best shown in detail in Fig. 5, are retractable supporting bolts 36 extending at their outer ends into seats or openings formed in the side frame members 19. Since these openings are formed in the frame members of the standard machines now in use no alterations are required for accommodating this supporting attachment. A coiled compression spring 37 is mounted within the tubular support 28 between the inner ends of the bolts 36 urging the latter outwardly into supporting position, as shown in Fig. 5. Guide pins 38 are attached to the inner ends of the bolts 36 running in elongated slots 39 in the tube 28 and serving as operating handles whereby the bolts 36 can both be retracted at the same time merely by engaging both handles at the same

time and pushing them toward each other, thus releasing the bolts from their supporting positions in the frame members 19.

As above mentioned, the carbon supply supporting carriage 30 is supported by the supporting framework above described for longitudinal reciprocating movement.

In the embodiment shown this reciprocating carriage embodies end plates or frame members 40 and a bottom plate or frame member 41 connected at its opposite ends to the end plates. The end plates 40 are each provided near their upper edge with openings 40' through which extend in loose relation the side frame members 29 of the stationary supporting frame. These end plates are thus slidably mounted for longitudinal reciprocating movement upon the supporting rods 29. Each of the supporting rods 29 carries a guide roller 42 for the carbon strips rotatably mounted thereon, as best seen in Fig. 4.

The longitudinally reciprocating carbon supply carriage 30 provides a support for the carbon supply spools 43, two of which are shown in the present embodiment, one being rotatably mounted in the end plates 40 at each of the opposite sides of the carbon supply device. As many carbon strips 44 as desired may be wound on each spool, two being shown for illustrative purposes but ordinarily there are three or more strips thus wound on each spool. For making only one or two carbon copies it will be sufficient to mount a single carbon strip on each supply spool. Each spool has a spindle 45 providing the rotary support for the spool and preferably a cylindrical supporting core 46 is mounted upon the spindle and carries the supply roll of carbon strips.

As best shown in Figures 9 and 13 each supply spool 43 has an end flange 47 rigidly connected to the spool for rotation therewith and having firmly attached at its outer surface a crown ratchet wheel 48 having outwardly disposed ratchet teeth. A transverse rotary locking shaft 49 is rotatable in appropriate bearings connected to the adjacent end frame 40 and carries a locking pawl 50 in position for cooperating in locking relation with the teeth of the adjacent ratchet wheel 48 for each supply spool. As best shown in Fig. 14 each pawl 50 is carried by a supporting sleeve 51 rotatably mounted on the shaft 49, and locating and guiding sleeves 52 are mounted on the shaft 49 at each of the opposite ends of the supporting sleeve 51. One of the sleeves 52 has a peripheral slot 53 in which runs a pin 54 fixed to the adjacent end of the supporting sleeve 51. The sleeves 52 are attached to the shaft 49 as by means of set screws. A tension spring 55 is connected to the lower end of each pawl 50 and anchored to the adjacent frame plate 40, thus tending to rotate the sleeve 51 until the stop pin 54 engages the seat at the end of the slot 53. The locking pawls are thus yieldingly urged forwardly by the spring into their locking positions.

Fixedly mounted upon the locking shaft 49 is a crank arm 56 and positioned for engagement with an operating pin 57 mounted upon a stationary supporting arm 58 that may be conveniently attached to or form an extension of the frame attaching block 35.

As best shown in detail in Figures 3 and 10, there is an operating means 59 supported in a bracket 60 connected to a transverse frame member 61 of the typewriting machine. This operating device embodies a sleeve or tube 62 attached to the bracket 60 and having an interior longitudinal passageway in which is loosely mounted

the operating rod 63, which can slide freely longitudinally within its supporting tube. The inner end of the rod 63 has an angularly disposed connecting part 64 normally received within an opening or slot in the connecting bracket 65 attached to the adjacent side of the end plate 40. For maintaining the operating rod 63 in its connected position, as shown in Fig. 10, there is a transverse pin or crosshead 66 rigidly attached to the rod 63 and running in elongated grooves 67 in the opposite walls of the supporting tube. At the outer end of the supporting tube 62, or the end nearest to the operator, there is a latching device embodying a latching lug 68 that may, as shown, be integral with the tube wall and two cooperating slots or notches 69 formed on the under side of the rod 63. A looped spring 70 is turned about the protruding end of the rod 62 and connected to the adjacent end of the supporting tube 62 and stressed to urge the notches of the rod into engagement with the latching lug 68. The outer end of the rod is provided with an operating handle 71.

Referring more particularly to Figures 2, 3 and 25 4, it will be seen that upright supports 72 extend upwardly from the supply carriage 30, one such support being positioned substantially at each of the four corners of the carriage. Each of these supports is provided with a guideway or slot 73 30 and in the form shown is an integral extension of the respective end plate 40. The guideways 73 are longitudinally aligned at opposite sides of the carriage.

The carbon strip turners 74 are mounted in 35 these upright supporting guideways. While for some purposes the carbon strip turners may vary in structure, a very convenient form is shown, especially in Fig. 8, as embodying a metallic framework preferably of light metallic wire and 40 having a supporting side 75 relatively heavier and stronger than the other two sides that, as shown, may be also of light wire. The frame is substantially triangular, being shown in the form of a right-angle triangle, the diagonal 76 of which 45 forms the turning edge about which the carbon strips 44 are caused to turn from their transverse course into the longitudinal course between the record strips. The third side 77 of the turning frame constitutes a support and brace for 50 the other sides. The sides 76 and 77 may be riveted or welded to the supporting side or attached in other convenient manner.

At its opposite ends the supporting side 75 of the strip turning frame is formed with extensions 55 78 providing pivot supports that are positioned for reception in the upright slots or guideways 73. Guiding and positioning collars 79 are preferably firmly attached adjacent to each of the supporting pivots 78 for guiding and positioning the 60 frames in the supporting guideways. One of the strip turning frames, as shown in Fig. 8, is provided with a supporting or stop lug 80 positioned oppositely to the frame side 77 for cooperation with a supporting bracket 81 mounted on one 65 of the end plates 40 adjacent to the upright guideways 73 thereof. As shown in the drawings, as many of these guide frames as desired for controlling the required number of carbon strips may be mounted in the supporting slots or guideways 73. It will also be noticed that the frame supporting sides of the turning frames 74 function as guides for guiding the carbon strips inwardly into interleaved relation with the record strips.

Fig. 7 is a partially diagrammatic showing of

the transfer strips 41 in interleaved transfer relation with the record strips of the record assembly 21 as they are arranged substantially at the writing area of the platen. It will be noticed that the record strips are fanfolded or, in other words, constructed of a single continuous strip of paper longitudinally folded at opposite longitudinal edges of the assembly, but they may be separate if desired.

If it is desired to employ one or more narrow carbon strips, one or more of the strip turning frames 74 may be correspondingly shortened. In other words, such a narrow record strip may be desired for receiving transfer inscriptions of only a part of the data to be recorded on the other record strips, and, in this instance, the carbon strip will be made narrower than the others to conform to the width of the narrow record strip. In this case the free swinging end of the strip turning frame for the narrow carbon will be short of the free swinging ends of the other strip turners.

A modified embodiment of the automatic holding device for the carbon supply spools is shown in Fig. 15. In this embodiment the function and arrangement of the parts are quite similar to those above described and particularly shown in Fig. 13, and corresponding parts are designated by the same reference numerals with the addition of the index *a*. In this embodiment the carbon supply spools 43a are substantially the same as above described and similarly mounted, but the crown ratchet wheel 48 has been omitted and in its place a friction holding device is provided.

As shown in Fig. 15 there is a friction element 82 of rubber, fibreboard or other similar material adapted to have frictional engagement with the outside surface of the spool flange 47a. The friction element 82 is supported at the outer end of a rocker arm 83 rigidly mounted upon the rotary locking or holding shaft 49a, mounted in a manner similar to that of the locking shaft 49 set forth above. This shaft 49a carries an operating arm 56a positioned for engagement by an operating pin 57a mounted upon the supporting bracket 58a. A tensioned coil spring 55a is connected to an arm 84 rigidly mounted upon the shaft 49a, thus holding the friction element in frictional engagement with the flange of the spool. When the carbon supply carriage is moved forwardly the operating pin 57a engages with the arm 56a to release the friction element 82 from its engagement with the spool flange. The outer surface of the flange 47a forms an endless uninterrupted friction surface with which the friction element 82 can engage in friction holding relation in any angular or rotative position of the spool.

In operation the carbon strips 44 are pulled from their supply spools and threaded into interleaved transfer relation with the record strips as shown in Figs. 2 and 7. For this purpose, the strip turning frames 74 can be easily removed from their supporting guideways 73 and the frame over which the carbon strip is being threaded can be swung upwardly on its pivotal mountings in the guideways, thus facilitating the threading of the carbon strip into position. Each carbon strip is extended upwardly over the strip guides 42 and 75 and then turned downwardly over the diagonally disposed turning side 76 of the frame. The positioning collars 79 are located contiguous to each other as seen in Fig. 3 so as to function as spacers for the guides 75 75

thus assuring at all times the proper guide spacing to provide freedom of movements of the transfer strips. Each successive carbon strip is thus threaded into its proper relation with the record strips as shown in Fig. 7. When the interleaved carbon strips are thus pulled forwardly into their active transfer position upon the platen 20 the forward ends thereof are normally positioned slightly short of the adjacent ends of the record strips that are clamped beneath the clamping bar 25. When the strips are thus disposed the carbon supply carriage 30 is in its rearward position, as shown in Fig. 2, and the writing is then made by the typewriting machine to fill in the desired data upon the set of forms ordinarily provided on the record strips. Successive blank forms are thus moved into writing position and inscribed with the same portions of the carbon strips.

When the used portions of the carbon strips become depleted to make it desirable to introduce fresh carbon areas, this can be done very quickly and easily as follows: The clamping bar 25 is released and the inscribed lengths or form sheets of the record strips are pulled forwardly until the lines of severance between adjacent form sheets or the lines of perforation are some little distance short of the severing edge of the bar 25, the carbon supply carriage 30 is then moved to its forward position by the operator who lifts the operating rod 63 in its tubular support 62, thus releasing the latching device 68, 69 whereupon the rod is pulled forwardly to correspondingly move the carriage forwardly. During this movement the operating pin 57 engages the arm 56 to release the pawl 50 from its holding position, thus enabling the supply spools to pay out fresh carbon strips. The record and carbon strips are then grasped together and pulled forwardly as a unit until the next tear off line or perforations 21' between sets of forms is at the edge of the tear-off bar 25. The tear-off bar is then let down into clamping position and the forward ends of the record and carbon strips are torn off at the same time. This action brings fresh carbon material into transfer relation with the next successive set of forms. The clamping bar 25 is again released and the carbon supply carriage is then moved rearwardly upon its supports to its normal operative position, shown in Fig. 2. This is done by grasping the operating rod 63, moving it upwardly to release the latching members 68, 69 and pushing the rod inwardly to the position shown in Fig. 10, whereupon the latching means 55 is again automatically engaged by the action of the spring 70. This movement also automatically locks the carbon spools against paying out the carbon strips. The forward ends of the record strips are then moved forwardly relatively to the carbon strips and introduced in clamped relation under the clamping bar 25, whereupon the typing may be continued with the fresh carbon material in transfer position. When the carbon spool holding device disclosed in Fig. 15 is used the operation of releasing and holding the carbon spools upon reciprocation of the carbon carriage is substantially the same as in the case of the alternative holding mechanism shown in Fig. 13. Due to the endless uninterrupted friction surface of the spool flange 47a the friction element 82 is effective to check and hold the spool in any rotative position thereof. The frictional pressure of the friction element 82 against the flange is maintained constant by the stressing of

the spring 55a thus assuring checking and holding the spool in any rotative position thereof.

It will be noted that the lower strip turning frame 14, as shown in Figures 3 and 4, having the support 80, 81 underlies the other frames in their normal operative position. Also, this arrangement permits all of the frames to move upwardly slightly on their pivots, thus providing a flexible mounting for the strip turning frames that results in avoiding binding or other obstruction to the forward movements of the record and transfer strips. This freedom of movement of the strips is particularly enhanced by the mounting of the turning frames for both pivotal and bodily or sliding movements in the upright slots or guideways 73 as described.

Since certain changes may be made in the above construction and different embodiments of the invention could be made without departing from the scope thereof, it is intended that all matter contained in the above description or shown in the accompanying drawings, shall be interpreted as illustrative and not in a limiting sense.

Having described my invention, what I claim as new and desire to secure by Letters Patent is:

1. The combination with a machine of the character described having a writing platen and side frame members disposed rearwardly of the platen, of a carbon supply device for supplying one or more carbon strips in transfer relation with record strips in writing position on the platen, means for mounting said supply device in operative position on said machine, means for guiding the carbon strip transversely into interleaved position with the record strips, one or more strip turning devices positioned in the courses of the record and carbon strips for turning the carbon strips into a longitudinal course in interleaved transfer relation with the record strips, and means mounting said turning device on said supply device for swinging movement in an upright plane and for bodily movements transversely of the plane of the record strips.

2. The combination with a machine of the character described having a writing platen and side frame members disposed rearwardly of the platen, of a carbon supply device for supplying one or more carbon strips in transfer relation with record strips in writing position on the platen, means for mounting said supply device in operative position on said machine, means for guiding the carbon strip transversely into interleaved position with the record strips, one or more strip turning devices positioned in the courses of the record and carbon strips for turning the carbon strips into a longitudinal course in interleaved transfer relation with the record strips, supports on said supply device each having an upright elongated guideway, and means pivotally mounting said turning device in the guideways of said supports for swinging movements away from the plane of the record strips and for sliding movements transversely of the plane of the record strips.

3. The combination with a machine of the character described having a writing platen and side frame members, of a carbon supply device for supplying a carbon strip in transfer relation with record strips in writing position on the platen, means for mounting said supply device in operative position on said machine, means for guiding the carbon strip transversely into interleaved position with the record strips, a strip turning device positioned in the courses of the record and carbon strips for turning the carbon

strips into a longitudinal course in interleaved transfer relation with the record strips, means pivotally mounting said turning device on said supply device for swinging movement in an upright plane, and a support for said strip turning device including a lug mounted on the latter outside of said pivotal mounting means for limiting its downward swinging movement substantially in the plane of the record strips.

4. The combination with a machine of the character described having a writing platen and side frame members, of a carbon supply device for supplying carbon strips in transfer relation with record strips in writing position on the platen, means for mounting said supply device in operative position on said machine, means for guiding the carbon strips transversely into interleaved position with the record strips, strip turning devices positioned in the courses of the record and carbon strips for turning the carbon strips into a longitudinal course in interleaved transfer relation with the record strips, supports on said supply device each having an upright elongated guideway, means mounting said turning devices in the guideways of said supports for swinging movements away from the plane of the record strips and for sliding movements transversely of said plane, and a support for one of said strip turning devices including a lug mounted on the latter outside of said pivotal mounting means for limiting its downward swinging movement substantially in the course of the record strips.

5. The combination with a machine of the character described having a writing platen and side frame members, of a carbon supply device for supplying one or more carbon strips in transfer relation with record strips in writing position on the platen, supporting members connected to said supply device and spaced longitudinally thereof for supporting the same in operative position on the machine, said supporting members including a supporting lug for engagement in supporting relation with the machine, and including also a longitudinally spaced retractable supporting member adapted to engage in supporting relation with one of said side frame members and being retractable into a releasing position.

6. The combination with a machine of the character described having a writing platen and side frame members, of a carbon supply device for supplying one or more carbon strips in transfer relation with record strips in writing position on the platen, supporting members connected to said supply device and spaced longitudinally thereof for supporting the same in operative position on the machine, said supporting members including a supporting lug for engagement in supporting relation with the machine and including also a pair of laterally oppositely disposed retractable supporting members adapted to engage in supporting relation with each of said side frame members and being retractable into releasing positions, said carbon supply device being proportioned so as to be inserted into operative position between said side frame members where it is held by said supporting members.

7. The combination with a machine of the character described having a writing platen and side frame members, of a carbon supply device for supplying one or more carbon strips in transfer relation with record strips in writing position on the platen, said carbon supply device including a longitudinally reciprocating supporting

carriage on which the transfer strip supply is carried, means for detachably mounting said supply device on the machine, an operating member including a longitudinally reciprocal operating rod connected to the forward end of said carriage and supported by the machine, latching means connected to said operating member for retaining said carriage in its forward or rearward positions, a guideway for retaining said operating rod in its operative position for longitudinal reciprocation, means carried by said carriage for guiding the transfer strips transversely into interleaved position with the record strips, and strip turning devices pivotally connected to said carriage for turning the carbon strips into a longitudinal course in interleaved transfer relation with the record strips.

8. The combination with a machine of the character described having a writing platen and side frame members, of a carbon supply device for supplying one or more carbon strips in transfer relation with record strips in writing position on the platen, said carbon supply device including a longitudinally reciprocating supporting carriage on which the transfer strip supply is carried, means for detachably mounting said supply device on the machine, operating means for said reciprocating carriage including an operating rod connected to the carriage and extending forwardly therefrom and attached to the machine for longitudinal movement, and a latching device connected to said operating means for retaining said carriage in its forward or rearward positions.

9. The combination with a machine of the character described having a writing platen and side frame members, of a carbon supply device for supplying one or more carbon strips in transfer relation with record strips in writing position on the platen, said carbon supply device including a longitudinally reciprocating supporting carriage on which the transfer strip supply is carried, operating means for said reciprocating carriage including an operating rod connected to the carriage, a tubular support in which said operating rod is mounted for relative longitudinal movements to effect reciprocation of said carriage and for lateral movements with reference to the tubular support, a latching device cooperating with said rod for holding said carriage in its forward or rearward position, and means for releasing said latching device by lateral movements of said rod with reference to its tubular support.

10. The combination with a machine of the character described having a writing platen and side frame members, of a carbon supply device for supplying one or more carbon strips in transfer relation with record strips in writing position on the platen, said carbon supply device including a longitudinally reciprocating supporting carriage on which the transfer strip supply is carried, operating means for said reciprocating carriage including an operating rod connected to the carriage, a tubular support in which said operating rod is mounted for relative longitudinal movements to effect reciprocation of said carriage and for lateral movements with reference to the tubular support, a guideway for retaining said rod in its normal connected operative position while permitting longitudinal reciprocation, a latching device including latching formations on said rod and tubular support for holding the carriage in its forward and rearward positions, means for controlling said latching device b

means of relative movements of said rod and tubular support, and means for urging said latching formations into latching engagement.

11. The combination with a machine of the character described having a writing platen and side frame members, of a carbon supply device for supplying one or more carbon strips in transfer relation with record strips in writing position on the platen, said supply device including a supporting frame, a carbon supply carriage mounted for longitudinal reciprocation on said supporting frame, one or more carbon strip supporting spools rotatably mounted on said carriage, a friction holding device including a friction element mounted for movement into engaging and disengaging positions with a continuous endless friction surface of said supply spool, a spring connected to said friction holding device and stressed to urge said friction element into frictional engagement with said friction surface to retain the spool from paying out carbon strip therefrom, and automatic means operated by longitudinal movements of said carriage for releasing said friction holding device.

12. The combination with a machine of the character described having a writing platen and side frame members, of a carbon supply device for supplying carbon strips in transfer relation with record strips in writing position on the platen, said supply device including a supporting frame, a carbon supply carrier mounted for longitudinal reciprocation on said supporting frame, a carbon strip supporting spool rotatably mounted on said carriage, strip turners positioned in the courses of the record and carbon strips for turning the carbon strips from said supply spool from a transverse course into a longitudinal course in interleaved transfer relation with the record strips, longitudinally spaced supports mounted on said carriage at each of the opposite sides of the strip path and each having an upright elongated receiving slot, pivots at opposite ends of each of said turners for mounting the latter one above another in said upright receiving slots both for pivotal movements and for bodily sliding movements, and spacers mounted on said strip turners for spacing the superposed turners.

13. In a machine of the character described, in combination, a strip turning device for turning a continuous transfer strip from a transverse course into the longitudinal course of continuous record strips in transfer relation therewith, said transfer strip turning device being positioned in the courses of the record and transfer strips and having a guide part, engaging the transfer strip, and a mount for said turning device mounting it for swinging movements transversely of the plane of the record strips and for bodily movements transversely of the plane of the record strips.

14. In a machine of the character described, in combination, a plurality of strip turning devices for turning continuous transfer strips from transverse courses into the longitudinal course of continuous record strips in transfer relation therewith, said turning devices being positioned in the courses of the record and transfer strips and having guide parts engaging the respective transfer strips, mounting devices for said turning devices including supports having elongated guideways extending transversely of the plane of the record strips and connections on the turning devices connecting them with the respective guideways for swinging movements and for bodily sliding movements transversely of the plane of the record strips.

15. In a machine of the character described, in combination, a plurality of strip turning devices for turning continuous transfer strips from transverse courses into the longitudinal course of continuous record strips in transfer relation therewith, said turning devices being positioned in the courses of the record and transfer strips and having guide parts engaging the respective transfer strips, mounting devices for said turning devices including supports having elongated

guideways extending transversely of the plane of the record strips, connections on the turning devices connecting them with the respective guideways for swinging movements and for bodily sliding movements transversely of the plane of the record strips, and spacers mounted on said strip turners for spacing the superposed turners in said guideways.
